UNITED STATES PATENT OFFICE.

SILAS S. BRADSHAW, OF BROOKLYN, NEW YORK.

DESIGN FOR A CAR-WINDOW SASH.

SPECIFICATION forming part of Design No. 26,682, dated February 23, 1897.

Application filed December 23, 1896. Serial No. 616,813. Term of patent 14 years.

To all whom it may concern:

Be it known that I, SILAS S. BRADSHAW, a citizen of the United States, residing in Brooklyn, Kings county, State of New York, have 5 invented and produced a new and original Design for Car-Window Sashes, of which the following is a specification.

In the accompanying drawings, forming a part hereof, Figure 1 is a front elevation of 10 a car-window sash, showing my design; and Fig. 2 is a vertical sectional view at line X X of Fig. 1.

Similar numerals of reference, wherever

they occur, indicate corresponding parts in both figures. 15

The leading feature of my design consists in the window-sash having depressions in its side stiles.

9 is a finger-lift upon rail 2, and 10 is a lock.

What I claim is—

The design for a car-window sash, substantially as shown and described. 20
